UNITED STATES PATENT OFFICE

LEWIS F. MOORE, OF ROANOKE, AND PRESTON CRAIGHILL, OF LYNCHBURG, VIRGINIA,
ASSIGNORS TO WALKER MACHINE & FOUNDRY CORPORATION, OF ROANOKE, VIR-
GINIA, A CORPORATION OF VIRGINIA

DESIGN FOR A TABLE

Application filed October 6, 1930. Serial No. 37,161. Term of patent 14 years.

To all whom it may concern:

Be it known that we, LEWIS F. MOORE and PRESTON CRAIGHILL, citizens of the United States, residing, respectively, at Roanoke, county of Roanoke, State of Virginia, and Lynchburg, county of Campbell, State of Virginia, have invented a new, original, and ornamental Design for Table, of which the following is a specification, reference being had to the accompanying drawing, forming a part thereof.

Figure 1 is a plan view of the table of which only one-half is shown, it being understood that the other half is identical, and

Figure 2 is a side view.

We claim:

The ornamental design for a table, substantially as shown and described.

LEWIS F. MOORE.
PRESTON CRAIGHILL.
